LOUIS ZWEIG, OF BROOKLYN, NEW YORK, ASSIGNOR TO SUN RISE LAMP MFG. CO., INC., A CORPORATION OF NEW YORK

DESIGN FOR A LAMP OR ANALOGOUS ARTICLE

Application filed January 2, 1930. Serial No. 34,001. Term of patent 3½ years.

To all whom it may concern:

Be it known that I, LOUIS ZWEIG, a citizen of the United States and a resident of the city of Brooklyn, county of Kings, and State of New York, have invented a new, original, and ornamental Design for Lamps or Analogous Articles, of which the following is a specification, reference being had to the accompanying drawing, forming a part hereof.

I claim:

The ornamental design for a lamp or analogous article substantially as shown.

LOUIS ZWEIG.
